UNITED STATES PATENT OFFICE

165,225

ELECTRIC MOTOR HOUSING

Harry Goodman, Britton, Okla.

Application June 19, 1950, Serial No. 10,619

Term of patent 14 years

(Cl. D26—5)

To all whom it may concern:

Be it known that I, Harry Goodman, a citizen of the United States, residing in Britton, Oklahoma, have invented a new, original, and ornamental Design for an Electric Motor Housing, of which the following is a specification, reference being had to the accompanying drawings, forming a part hereof.

Figure 1 is a front elevational view of an electric motor housing, showing my new design;

Figure 2 is an elevational view looking at the right hand side of the housing as viewed in Fig. 1;

Figure 3 is an elevational view of the other side of the housing;

Figure 4 is a top view;

Figure 5 is a rear elevational view;

Figure 6 is a bottom view;

Figure 7 is a perspective view looking down-

wardly at the front and left hand walls of the housing; and

Figure 8 is a similar view looking at the rear and right hand walls of the housing.

I claim:

The ornamental design for an electric motor housing, as shown.

HARRY GOODMAN.
